[57] CLAIM

The ornamental design for a picture hanger unit, as described and shown.

DESCRIPTION

FIG. 1 is a rear, exploded perspective view of a picture hanger unit showing my new design;

FIG. 2 is a top plan view thereof;

FIG. 3 is a bottom plan view thereof;

FIG. 4 is a side elevational view in the fully assembled position with the opposite side being a mirror image and with the broken line showing of structure being for illustrative purposes only and forms no part of the claimed design;

FIG. 5 is a rear elevational view fully assembled; and, FIG. 6 is a front elevational view fully assembled.

FIG. 5

FIG. 6
